UNITED STATES PATENT OFFICE.

ADOLPH E. RUDOLPH, OF JEFFERSONVILLE, NEW YORK.

IMPROVEMENT IN HARNESS ATTACHMENTS.

Specification forming part of Letters Patent No. **177,563**, dated May 16, 1876; application filed April 6, 1876.

To all whom it may concern:

Be it known that I, ADOLPH E. RUDOLPH, of Jeffersonville, in the county of Sullivan and State of New York, have invented a new and useful Improvement in Trace-Plates for Harness, which improvement is fully set forth in the following specification, reference being had to the accompanying drawing, in which—

Figure 1 represents the old form of harness attachment, which my invention is designed to supersede. Fig. 2 is a front view of my improved plate, showing the manner of fastening it to a trace. Fig. 3 is a rear view of the plate detached. Fig. 4 is a cross-section thereof.

Similar letters indicate corresponding parts.

My invention consists in a peculiarly-formed plate, which is intended to be permanently fastened to each of the traces of a harness for the purpose of facilitating the attachment to such traces of the following parts—that is to say, the saddle-strap, the girth, and the breeching-strap, the object of the plate being, also, to lessen the cost of the harness.

The plate is provided with laterally-projecting loops for the attachment or connection of the parts above enumerated, and provided with rivet-holes, whereby it is adapted to be firmly and permanently fastened to a trace, being, moreover, provided with flanges on two opposite edges, by which the plate is very firmly held in position after it has been fastened to a trace, as will be hereinafter more fully set forth.

In the drawing, the letter A designates the base or body of my plate, and B C D are its laterally-projecting loops. The loop B serves to receive a saddle-strap, E, while to the loop C, (which is situated directly opposite the loop B,) is attached the end of a girth, F. The loop D is intended to receive the end of a breeching-strap, G.

In the base or body of the plate are formed

holes a, (see Fig. 3,) which permit of securing the plate to a trace, H, by means of rivets b, as seen in Fig. 2, by which rivets the plate is firmly and permanently connected to the trace.

The letters I I designate flanges, which are formed on two opposite edges of the plate. The inner edges of these flanges are made of the shape of the edges of the trace, to which the plate is intended to be fastened, and in the present example are parallel with each other, the flanges being, moreover, placed at such a distance apart as to be capable of receiving the trace between them. When the plate is secured to a trace the flanges I I are made to abut against the opposite longitudinal edges thereof, and hence the strain of the saddle-strap, as well as the girth, which would otherwise fall on the rivets b, is borne by the flanges, and the plate is very firmly held in position.

The plate may be cast in one piece with the loops B C D, as well as the flanges I I, and the rivet-holes, without difficulty, and consequently its cost is small, while by the use of the plate the cost of a harness is considerably reduced, compared with the cost of the old style of harness represented in Fig. 1 of the drawing.

The old style of harness just referred to is too well known to here need description.

What I claim as new, and desire to secure by Letters Patent, is—

A trace-plate for harness, constructed with laterally-projecting loops B C D, rivet-holes a, and flanges I I, substantially as described.

In testimony that I claim the foregoing I have hereunto set my hand and seal this 30th day of March, 1876.

A. E. RUDOLPH. [L. S.]
